WINDOW REGULATOR

William C. Devereaux, Detroit, Mich.

Application May 8, 1939, Serial No. 272,535

9 Claims. (Cl. 268—126)

This invention relates generally to window regulators for motor vehicle bodies and refers more particularly to improvements in regulators for operating ventilating windows of the type supported for sliding movement fore and aft of the vehicle body.

One type of ventilation commonly employed in motor vehicle bodies consists in providing a slot at the front edge of one window panel by sliding the latter rearwardly in the plane of the window opening. In accordance with conventional practice, the window panel is shifted fore and aft of the vehicle body to respectively close and open the ventilating slot by the regulator mechanism provided for raising and lowering the window panel. Although various different types of regulators have been proposed for accomplishing the required shifting movement of the panels, nevertheless, many of these regulators have proved so complicated and expensive in construction as to seriously detract from the simplicity of the principle of ventilation outlined above. Moreover, in many instances, the regulators provided in the past for ventilating windows of the character referred to embody parts of such a nature as to render it extremely difficult to assemble the same in the minimum space usually existing between the body panels and, in addition, do not lend themselves to economical manufacture and assembly.

It is, therefore, one of the principal features of this invention to overcome the difficulties noted above by providing a window regulator composed of a relatively few simple parts capable of being readily assembled in a compact space and rendering it possible to shift the window fore and aft of the body as the regulator is manipulated to effect vertical movement of the window into and out of the window opening.

In addition to the above, the present invention contemplates a window regulator embodying means for guiding the closure panel in a straight line path of travel between the two extreme vertical positions of the panel and also prevents tilting movement of the panel in the plane of the window opening.

The foregoing, as well as other objects, will be made more apparent as this description proceeds, especially when considered in connection with the accompanying drawings, wherein—

Figure 1 is an elevational view partly in section of a part of a vehicle body illustrating a window regulator constructed in accordance with this invention;

Figure 2 is an enlarged elevational view of a

part of the regulator mechanism shown in Figure 1;

Figure 3 is a sectional view taken substantially on the plane indicated by the line 3—3 of Figure 1;

Figure 4 is a sectional view taken substantially on the plane indicated by the line 4—4 of Figure 2.

Figure 5 is a sectional view taken substantially on the plane indicated by the line 5—5 of Figure 3.

Referring now more in detail to the drawings, it will be noted that there is illustrated in Figure 1 a vehicle body door 10 having a window opening 11 and having a closure in the form of a glass panel 12 for closing the window opening. In accordance with conventional practice, the closure panel 12 is supported for vertical sliding movement into and out of the window opening 11 by means of a window regulator, designated generally in the accompanying drawings by the reference character 13. The window regulator 13 is supported upon the inner door panel 14 which, in turn, cooperates with the outer door panel 15 to form a well for receiving the closure 12 when the latter is in its lowermost position.

The window regulator mechanism 13, in addition to embodying means 16 for raising and lowering the panel 12 relative to the window opening, also comprises guide means 17 for effecting shifting movement of the panel 12 fore and aft of the body in the plane of the window opening. In the present instance, the guide means 17 causes the closure panel 12 to shift rearwardly in the plane of the window opening upon initial operation of the regulator means 16 for lowering the glass panel 12 relative to the window opening and, in addition, serves to shift the glass panel 12 forwardly during the final movement of the regulator means to window closing position. As will be presently described, the window regulator mechanism effects rearward shifting movement of the closure panel 12 a distance sufficient to form a ventilating slot 18 between the forward edge of the closure panel 12 and the adjacent body structure 19. The slot 18 is created by the regulator mechanism while the closure panel 12 is in its uppermost position with respect to the window opening so that the top edge of the panel remains adequately supported by the adjacent body structure when the panel is in its ventilating position.

Referring first to the guide means 17, it will be noted that this means comprises a plate 20 suitably secured to the inner panel 14 and supporting

- a carrier 21 for vertical sliding movement. The carrier 21 is operatively connected to a plate 22 secured at its upper end to a bracket 23 which, in turn, is fixed to the glass channel 24. The upper end of the plate 22 is detachably secured to the bracket 23 by means of the fastener element 25 and the lower edge of the glass panel 12 is secured in the channel 24, with the result that the panel moves as a unit with the plate 22.
- 10 In the present instance, the carrier 21 serves as an operator for the plate 22 and both of these members are guided by the plate 20 through the medium of a pair of slots 26 and 27 formed in the plate 20. In this connection, it will be noted that the upper end portion of the plate 22 is engaged with the slot 27 through the medium of a stud 28 secured to the plate 22 with the shank portion extending through the slot 27 and terminating in an enlarged head 29 of a diameter greater than the width of the slot to retain the stud in assembled relation with the plate 20. The lower end of the plate 22 is provided with a stud 30 having a shank portion extending through the slot 26 and terminating in an enlarged head 31 of a diameter greater than the width of the slot 26 to maintain the same in assembled relationship with the plate.
- 15 Upon reference to Figures 2 and 5, it will be noted that the upper ends of each of the slots 30 are spaced from each other a distance equal to the vertical spacing between the studs aforesaid and are provided with forwardly extending horizontal extensions 32 and 33, respectively. The arrangement is such that the plate 22, with the associated glass panel 12, are guided in a straight line vertical path when the studs on the plate 22 are in engagement with the vertical portions of the two slots and are guided in a forward direction by the extensions of the slots when the panel 35 is raised. It will, of course, be understood that the upper ends of the two slots in the plate 20 extend to such a point that when the studs on the plate 22 assume a position adjacent the entrant ends of the extensions of the slots, the closure panel 12 is in its uppermost position with respect to the window opening so that the top edge of the closure panel 12 is supported by the adjacent body structure. However, in this position, the forward edge of the panel 12 is spaced rearwardly from the adjacent body structure to provide the slot 18 and the lengths of the extensions 32 and 33 at the upper ends of the slots in the plate 20 are such as to provide the forward movement of the plate 22 required to effect closing of the slot 18 by the panel 12.
- 40 It has previously been stated that the plate 22 is operated by the carrier 21. As shown in Figures 2 and 3, the carrier 21 is provided with two vertically spaced studs 34 and 35 having shank portions respectively extending through the slots 26 and 27 and having enlarged head portions 36 of a diameter greater than the width of the slots to insure maintaining the carrier in assembled relation with the plate 20. The stud 35 is mounted on the carrier 21 at a point below the stud 28 on the plate 22 and is operatively connected to the stud 28 by means of linkage 37. The linkage 37 comprises a link 38 having the lower end connected to the stud 35 and having the upper end 45 connected to an intermediate link 39 by means of a pivot pin 40. The opposite end of the link 39 is pivotally connected to the lower end of a link 41 by means of a pin 42 and the upper end of the link 41 is pivotally connected to the stud 28. In 50 this connection, attention is called to the fact

that the linkage is maintained in sliding engagement with the adjacent side of the plate 20 by means of coil springs 42 respectively surrounding the shank portions of the studs 28 and 35 between the linkage and the adjacent portions of the carrier. As a result, the springs cooperate with the linkage to maintain the heads of the studs in frictional engagement with the plate 20 so as to prevent rattling of the parts. It will also be observed that the pivot pins 40 and 42 have shank portions which extend through the slot 27 and terminate in enlarged heads in the same manner as the studs 28 and 35.

55 The stud 34 at the lower end of the carrier 21 is operatively connected to the stud 30 at the corresponding end of the plate 22 by means of linkage 43 exactly the same as the linkage 37 previously described. Also, the studs 30 and 34 are provided with coil springs 44 similar to the coil springs 42 in that they maintain the linkage and the head portions of the studs in frictional contact with the plate 20. Attention is directed to the fact at this time that the distance between the studs on carrier 21 and the studs on the plate 22 is such that the carrier 21 moves in a straight line path of travel during vertical and horizontal shifting movement of the plate 22 and associated glass panel 12.

60 The carrier 21 is operated by the regulator operating means 16, shown in Figure 1 as having a segment 45 supported on the inner door panel 14 for rocking movement and adapted to mesh with a pinion 46 which, in turn, is driven by the usual operating handle (not shown). The segment 45 is operatively connected to the carrier 21 by means of a regulator arm 47 having one end secured to the segment 16 and having a stud 48 at the opposite end slidably engaging in a horizontally elongated slot 49 formed in the carrier 21 adjacent the upper end of the latter. In accordance with conventional practice, the stud 48 is provided with an enlarged head insertable through the enlarged portion 50 of the slot 49 and having a diameter exceeding the width of the remaining portion of the slot to insure maintaining the parts in assembled relationship.

65 The extent of downward travel of the carrier 21 required to completely lower the panel 12 in the door 10 is determined by suitable stops 51 secured to the plate 20 for abutting engagement with the studs 34 and 35. The portions 52 of the slots 26 and 27 projecting downwardly from the stops 51 are enlarged to such an extent to permit the head portions of the two series of studs to be readily assembled with and removed from the plate 20. In other words, the construction is such as to permit the carrier 21, plate 22, bracket 23, glass channel 24 and the closure panel 12 to be assembled with or removed from the plate 20 as a unit. Also, due to the readily detachable connection between the regulator arm 47 and the carrier 21, it follows that the above assembly is also capable of being readily connected to or removed from the regulator operating means 16.

Operation

70 Assuming that the closure panel 12 is in its lowermost position out of the window opening and that it is desired to close the window opening by the panel, it will be noted that the pinion 46 is rotated by the usual handle (not shown) to effect a rocking movement of the regulator arm 47 through the medium of the segment 16. In the above position of parts, the pinion 46 is, of course, manipulated to lift the free end of the 75

regulator arm and since the latter is connected to the carrier 21, it follows that the latter will also be raised relative to the plate 20. The carrier is guided in a straight line vertical path by the two series of studs respectively engaging in the vertical portions of the slots 26 and 27. As previously stated, the plate 22, carrying the closure panel 12, is operatively connected to the carrier 21 through the medium of the linkage 10 32 and 33. As a result, the closure panel 12 is raised as a unit with the carrier 21 in a vertical straight line path of travel.

When the carrier 21 has been raised by the regulator arm 47 to a position wherein the studs 15 28 and 30 are at the upper ends of the vertical portions of the slots 26 and 27, the glass panel 12 is in its uppermost position with respect to the window opening 11. However, in this latter position of the glass panel, the front edge of the 20 same is spaced from the adjacent body structure to provide the ventilating opening 18, with the result that the air stream flowing past the outer side of the slot 18 draws air through the slot from the interior of the body.

25 In the event it is desired to close the ventilating slot 18, movement of the carrier 21 in an upward direction by the regulator arm 47 is continued, with the result that the extensions at the upper ends of the slots in the plate 20 change 30 the direction of movement of the studs 28 and 30 to a horizontal forward movement. Inasmuch as these studs are secured directly to the plate 22 and in view of the fact that the glass panel 12 is carried by the plate 22, it follows that the 35 panel will be shifted in a forward direction to close the ventilating slot 18.

It will be noted from Figure 2 that during the forward shifting movement of the panel 12, the lowermost studs 34 and 35, carried by the carrier 40 21, remain in the vertical portions of the slots 26 and 27, with the result that the direction of movement of the carrier 21 is not changed. It follows, therefore, that the carrier 21 is moved 45 in a straight line vertical path of travel notwithstanding that the glass panel is shifted fore and aft of the body.

When it is desired to lower the glass panel 12, the pinion 46 is rotated in the opposite direction to effect a downward movement of the carrier 21 50 by the regulator arm 47. Initial downward movement of the carrier 21 is effected relative to the plate 22 and the latter is merely moved rearwardly in a direction parallel to the extensions 32 and 33 of the slots in the plate 20. Of course, 55 continued downward movement of the carrier 21 eventually causes the uppermost studs 28 and 30 on the plate 22 to enter the vertical portions of the slots on the plate 20 and thereby move downwardly as a unit with the carrier 21.

60 Thus, from the foregoing, it will be observed that I have provided a window regulator composed of a relatively few simple parts capable of being inexpensively manufactured, assembled and installed. It will also be noted that my invention 65 proved regulator mechanism effectively guides the closure panel in a straight line path of travel between the two extreme vertical positions of the panel and at the same time causes fore and aft shifting movement of the panel relative to the 70 window opening to effect ventilation of the interior of the body.

What I claim as my invention is:

1. The combination with a vehicle body having a window opening and a closure for the window 75 opening mounted for vertical sliding movement

into and out of the window opening, of a regulator for said closure comprising a plate fixed against movement with said closure and having laterally spaced vertically extending guiding portions provided with forwardly projecting extensions at the upper ends thereof, followers carried by the closure respectively slidably engaging the guiding portions and cooperating with the extensions to effect fore and aft shifting movement of the closure, a pair of followers respectively 10 slidably engaging the vertically extending parts of said guiding portions, linkage respectively pivotally connecting the second named followers with the first mentioned followers and means connected to the second mentioned followers for 15 raising and lowering said closure relative to said plate.

2. The combination with a vehicle body having a window opening and a closure for the window 20 opening mounted for vertical sliding movement into and out of the window opening, of a regulator for said closure comprising a plate fixed against movement with said closure and having laterally spaced vertically extending guiding portions provided with forwardly projecting extensions at the upper ends thereof, followers carried by the closure respectively slidably engaging the guiding portions and cooperating with the extensions to effect fore and aft shifting movement 25 of the closure, a carrier having followers respectively slidably engaging the guiding portions on said plate, linkage connecting the followers on said carrier to the followers carried by said closure, and means connected to the carrier for raising and lowering said closure. 30

3. The combination with a vehicle body having a window opening and a closure for the window opening mounted for vertical sliding movement into and out of the window opening, of a regulator for said closure comprising a plate 40 fixed against movement with said closure and having laterally spaced vertically extending guiding portions provided with forwardly projecting extensions, a member carried by the closure and having spaced followers slidably engageable with 45 said guiding portions and cooperating with the extensions to effect fore and aft shifting movement of the closure, a carrier having laterally spaced followers respectively slidably engaging the sliding portions on the plate, linkage connecting the followers on the carrier with the followers on said member, and means operatively connected to the follower for raising and lowering 50 the latter relative to said plate.

4. The combination with a vehicle body having a window opening and a closure for the window opening mounted for vertical sliding movement into and out of the window opening, of a regulator for said closure comprising a plate 60 fixed against movement with said closure and having laterally spaced vertically extending guiding portions provided with forwardly projecting extensions, a member carried by the closure and having spaced followers slidably engageable with 65 said guiding portions and cooperating with the extensions to effect fore and aft shifting movement of the closure, a carrier having laterally spaced followers respectively slidably engaging the sliding portions on the plate, linkage connecting the followers on the carrier with the followers on said member, and means operatively connected to the carrier for raising and lowering 70 the latter including an arm connected to the carrier for sliding movement relative thereto in 75

a direction transverse to the direction of sliding movement of the carrier.

5. The combination with a vehicle body having a window opening and a closure for the window opening mounted for vertical sliding movement into and out of the window opening, of a regulator for said closure comprising a plate fixed against movement with said closure and having laterally spaced vertically extending slots therethrough provided with forwardly projecting extensions at the upper ends thereof, a member carried by the closure and having spaced followers respectively slidably engageable with said slots and cooperating with the extensions to effect fore and aft shifting movement of the closure, a carrier having followers respectively slidably engageable with said slots, linkage pivotally connecting the followers on the carrier with the followers on said member, and means operatively connected to the carrier for raising and lowering said carrier.

6. The combination with a vehicle body having a window opening and a closure for the window opening mounted for vertical sliding movement into and out of the opening, of a regulator for said closure comprising a plate fixed against movement with said closure and having a vertically extending guiding portion provided with a forwardly projecting extension at the upper end, a member carried by the closure and having a follower slidably engageable with the guiding portion and cooperating with said extension to effect fore and aft shifting movement of the closure, a carrier having a follower slidably engageable with the guiding portion and operatively connected to said member, and means connected to the carrier for raising and lowering the latter relative to said plate.

7. The combination with a vehicle body having a window opening and a closure for the window opening mounted for vertical sliding movement into and out of the opening, of a regulator for said closure comprising a plate fixed against movement with said closure and having laterally spaced vertically extending guiding portions, one of the vertically extending guiding portions having a forwardly projecting extension at the upper end, a member carried by the closure and having a follower slidably engageable with the last named guiding portion on the plate and cooperating with the extension on the

latter guiding portion to effect fore and aft sliding movement of the closure, a carrier having a follower slidably engageable with the other guiding portion and operatively connected to said member, and means connected to the carrier for raising and lowering the latter relative to said plate.

8. The combination with a vehicle body having a window opening and a closure for the window opening mounted for vertical sliding movement into and out of the opening, of a regulator for said closure comprising a plate fixed against movement with said closure and having a vertically extending guiding portion, said vertically extending guiding portion having a forwardly projecting extension at the upper end, a member carried by the closure and having a follower slidably engageable with the guiding portion on said plate and cooperating with the extension on the latter guiding portion to effect fore and aft sliding movement of the closure, a carrier having a follower spaced below the follower on said member a distance greater than the length of said extension and engageable with said guiding portion, linkage connecting the two followers, and means connected to the carrier for raising and lowering the latter relative to said plate.

9. The combination with a vehicle body having a window opening and a closure for the window opening mounted for vertical sliding movement into and out of the opening, of a regulator for said closure comprising a plate fixed against movement with said closure and having laterally spaced vertically extending slots therethrough provided with forwardly projecting extensions at the upper end thereof, a member carried by the closure and having followers slidably engageable with said slots and cooperating with the extensions to effect fore and aft shifting movement of the closure, a carrier having followers respectively spaced below the followers on said member a distance greater than the length of the extensions and slidably engageable with the vertically extending portions of the slots, linkage respectively connecting the followers on the carrier with the followers on said member, and means for raising and lowering the carrier relative to said plate.

WILLIAM C. DEVEREAUX.
